SEWING MACHINE

Carl W. Johnson, Brooklyn, N. Y., assignor to
 American Machine & Foundry Company, a corporation of New Jersey

Application August 12, 1939, Serial No. 289,907.

41 Claims. (Cl. 112—171)

This invention relates to sewing machines and more particularly to a sewing machine of the under and over stitch type, utilizing a double pointed needle having an eye located between the points, and wherein the opposite ends of the needle are grasped alternately by the jaws of opposed needle bars in order to project the needle and thread through the work to form stitches.

A machine of this type has a wide variety of uses in the manufacture of gloves, novelty collars, handkerchiefs, other apparel, etc. It will be seen, therefore, that it is important in sewing these materials not to apply excess tension to the thread at any time, otherwise it might cut through the work, as in the case of soft leather used in glove making, or else it might be so over tensioned that the work would be puckered. Conversely, it is also necessary that the thread be properly tensioned, otherwise the work will be unsatisfactory and unsalable. It is, therefore, an object of my invention to provide means for properly tensioning the thread so that all danger of excess tension and under tension of the thread is eliminated.

It is also an object of my invention to eliminate substantially all possibility of fouling, fraying or splitting the thread by the needle as it moves through the work and to provide improved means for substantially eliminating the breakage of needles.

It is a further object of this invention to provide a sewing machine of the under and over stitch type, which is capable of sewing all kinds of materials without the necessity of using any auxiliary mechanism or device in conjunction therewith for successful and satisfactory operation.

It is a further object of this invention to prevent fouling of the thread both above and below the work and by providing mechanism for moving the thread out of the path of the needle and to prevent unnecessary stretching or pulling of the thread during the operation of the machine.

In order to meet all of the demands which may be imposed upon my machine in sewing all of the various kinds of materials which may be used, it may be necessary from time to time or during the sewing of any particular work to change the length of the stitch from long to short or vice versa, or to utilize a certain length-stitch for one part and another length-stitch for another, etc. For that reason my invention further consists in the provision of mechanism

which makes it possible to change the length of the stitch from time to time whenever necessary. This mechanism may operate automatically or be adjusted manually to change the length of the stitch whenever desired.

It is a further object of the invention to provide means for guiding the free end of the thread at the completion of each stitch in order that the thread may be properly disposed with respect to the needle and prevent fouling or clogging of the machine with the elimination of possible break downs or breakage of needles and/or thread.

It is a further object of the invention to provide means for clamping the thread at the proper time to deposit it in correct relationship with the needle and the work and to provide means for tensioning the thread and for moving it out of the path of the needle and eliminating any danger of fouling the needle.

It is also an object of this invention to provide means operating in timed relation with the reciprocating needle for throwing the thread out of the path of the needle on both sides of the work and on the up and down stroke of the needle.

This invention is further characterized by the provision of a drum cooperating with the thread pulling mechanism about which the thread is disposed by a thread puller during the operation of the needle and means, such as a flexible belt encircling the drum, for loosely holding the thread on the drum while at the same time allowing the thread puller to move therebeneath and position the loose end of the thread about the drum.

The invention also consists in the provision of thread holding means coacting with the needle on one of its strokes for holding the thread to prevent excess tension from being applied to the work during operation of the thread puller, and auxiliary means acting in conjunction therewith for holding the thread when said means release the thread and the needle is reciprocated in an opposite direction.

The invention also consists in the provision of means for holding the thread during the operation of the thread puller, and auxiliary holding means acting in conjunction therewith which hold the thread tensioned after it is released by the first means and move it upwardly with the needle and then displace it laterally out of the path of the needle and thread puller.

My invention is further characterized by the provision of means for minimizing movement of

the thread relative to the needle so that whenever the needle is projected through the work the thread will be positioned properly with reference thereto and uniform stitches will be formed.

My invention also consists in the provision of means for taking up the slack in the thread following the movement of the needle in one direction through the work and a device cooperating therewith for kinking the thread adjacent the needle so as to properly tension the thread and also prevent movement thereof relative to the needle on its next motion.

A principal object of my invention is to provide gripping means for holding the thread in order to prevent excess tension from being applied thereto during the pulling operation which would result in the formation of over-tight stitches.

An additional object is to provide means for disposing the thread laterally to prevent the thread puller from pulling more than a single loop of thread. This provision is made because of the fact that in a machine of this type where thread is disposed about a drum and the loop end is being pulled through the work, there is a tendency for the thread puller to engage with more than the one desired loop so that in the absence of means mentioned above, two or more loops of thread might be engaged by the puller and excess tension be applied to the work or the thread broken or fouled.

A further object of the invention is to provide a short thread sewing machine with a double pointed needle with means for laterally disposing the thread, and means acting in conjunction therewith for transferring the thread with a movement concurrent with that of the needle so that the resulting stitch will have the exact amount of tension desired and neither more nor less.

With these and other objects not specifically mentioned in view, the invention consists in certain combinations and constructions which will be hereinafter fully described, and then specifically set forth in the claims hereunto appended.

In the accompanying drawings which form a part of this specification, and wherein the several reference characters designate the same or like elements:

Figure 1 is a front elevation of the sewing machine;

Figure 2 is a partial side view of the same;

Figure 3 is an enlarged detail view showing the needle bars and material feeding mechanism;

Figure 4 is an enlarged end view of Figure 3;

Figure 5 is a detail view taken on line 5—5 of Figure 3 of the feeding mechanism and discloses means for adjusting the feed to lengthen or shorten the stitches;

Figure 6 is a partial plan view showing the thread guiding mechanism;

Figure 7 is an end view of the same taken on line 7—7 of Figure 6;

Figures 8, 9 and 10 are detail views to illustrate the manner in which the machine operates in sewing the work;

Figures 11, 12 and 13 are sectional views of Figures 8, 9 and 10 taken on line 11—11, 12—12 and 13—13, respectively;

Figures 14, and 15 are detail views of a portion of the thread guiding mechanism shown in Figure 7, in different working positions;

Figure 16 is a side elevation of a modified device for adjusting the length of the stitch;

Figure 17 is a side elevation of another modi-

fication for adjusting the length of the stitch in which it is possible to produce alternate short and long stitches; and

Figure 18 is an end view of Figure 17.

5 Referring to the drawings, Figures 1 and 2 show a preferred embodiment of my improved sewing machine comprising a stationary frame 10, a sewing machine head 11 extending therefrom, and a bracket 12 supporting the sewing machine 13. A motor 14, which is suspended from arms 15 supported by a bracket 16, attached to frame 10, is provided with a pulley 17 driving a belt 18 running over a pulley 19 integral with a clutch 20 (Figure 2) adapted to receive its co-acting clutch member 21. This clutch mechanism, which may be of the conventional cone type, when its parts are in driving relation, cause a pulley 22 which may be a part of member 21, to drive a belt 23 tracking a pulley 24 loosely mounted on stationary shaft 25, supported in a bearing in lug 26 and by the end wall 27.

20 Clutch member 21 is constructed and arranged to engage member 20 by means of a foot treadle 28 (Figure 1) which in being depressed actuates a rod 29 connected to an arm 30 to shift the member 21 into engagement with member 20. Arm 30, it will be observed, is mounted on shaft 31 supported by a housing 32 (Figure 2). In order to overcome some of the inertia of the machine and bring its movement to as quick a stop as possible, I have provided brake mechanism for that purpose. The movement of shaft 31 permits its shifter arm 33, in engagement with a collar 34, integral with a brake drum 35 mounted on shaft 36, to withdraw from the stationary brake member 37. Therefore, whenever treadle 28 is depressed and clutch members 20—21 are moved into operative engagement against the tension of a spring 39 stretched between post 40 and one 25 end of arm 30, brake member 35 is separated from active engagement with stationary brake member 37 and, consequently, shaft 36 rotates and drives the pulley 24. Bracket 38 attached to housing 32 supports the clutch shaft 36 and 30 also serves as a support for braking surface member 37. Whenever the operator's foot is removed from the treadle, spring 39 tends to disengage clutch members 20—21 and thereby interrupts the drive of pulley 34 and shaft 36, which permits the 35 pulley 19 to idle in neutral position. At this time the operator may turn the machine over manually by rotating hand wheel 41. If it is desired to lock the machine against movement, the operator can depress foot treadle 28 in a clockwise motion, which causes brake member 35 to move into engagement with braking surface 37 and thereby prevent forward rotation of the fly wheel 41.

40 If desired, means may be furnished for allowing the brake to be applied at any desired time after the disconnection of clutch members 20—21. In some instances, however, especially in sewing material such as gloves, where it is necessary to move the work around considerably in order to position stitches properly, it has been found desirable to retain the needle in work engaging position for a portion of the cycle so that it may act as a center about which the work is moved. In this manner, the presser foot can be lifted and the work shifted as desired, without disturbing the operative relationship of the needle and the work. One form of mechanism suitable for effecting this purpose has been shown in Figures 2 and 4. This mechanism consists of a connecting rod 280 pivotally joined to lever arm 30 at one 45

end and fixed at its other end to a bellcrank lever 281 mounted on a stud 285 carried by a bracket 286 suitably secured to the machine frame. Lever 281 is provided with a cam follower 282 arranged to track a cam surface 283 of a cam 284. The cam surface 283 is so designed that in the normal operation of the machine it will prevent braking surfaces 35 and 37 from movement into engagement until the cam follower 282 runs on the low portion of the cam surface 283, whereupon the needle will be positioned in the work and the brake can be moved into operative engagement with the surface 37 to stop the machine.

The pulley 24 is integral with a hand wheel 41 providing means for manually turning over the machine. Shaft 25 is also equipped with a sprocket 42, a looper cam 43, a gear 44 and a cam 45, these members being bolted together as a unit and revolving with pulley 24.

The cam 45 (Figures 3 and 4) is provided with a cam track 46 engaging cam followers 47-47 positioned at diametrically opposite points of the cam, these followers being carried by slides 48-48 guided by gibbs 49-49 bolted to the end wall 21 of the head 11. Each of the slides is provided with a lug 50 carrying a link 51 connected to the rear ends of their respective oscillating arms 52 and 53. Each of the arms 52 and 53 is mounted on an intermediate pivot stud 54 projecting from the head 11. An upper needle bar 55 and a lower needle bar 56, arranged in alignment, are provided with actuator arms 57 mounted upon a pivot stud 58 carried by a link 59 connected to their respective arms 52 and 53 whereby to convert the oscillatory motion of the arms into a reciprocating motion of the needle bars. The needle bars and their operating mechanism may be of the type disclosed in the Naftali Reissue Patent No. 19,653, granted July 23, 1935, and hence a detailed showing of the same in this application is deemed unnecessary. The upper needle bar 55 is guided in lugs 63 and 64 projecting from a support 65 attached to an extending portion 66 (Figure 4) of head 11. The lower needle bar 56 is guided in lugs 67 and 68 projecting from a holder 69 secured to the lower portion of head 11.

A double pointed needle 70 is provided; that is, one having a point at each end and a thread receiving eye located at about mid-length of the needle between the points. Each of the needle bars is equipped with tapered caps 72 serving to confine spring pressed jaws, which may be of the type shown in the above referred to patent, which clutch the needle to perform the stitching. It will be understood by those skilled in the art that in this type of machine the needle 70 is projected back and forth through the work and is, therefore, alternately grasped by the jaws of each needle bar. Briefly the action is such that as the oscillating arm 52 carries the needle bar 55 inwardly toward the work, the head 13 of the needle bar will abut the upper lug 63 and effect the release of the needle from the upper needle bar, the needle being grasped by the lower bar in the same manner as the upper bar. The upper needle bar, upon receiving the needle from the lower needle bar, starts to rise and elevates the head 13 from engagement with the lug 63. At the moment this occurs the spring pressed jaws clutch the needle by reason of the spring action in the needle bar 55, and the movement of the jaws into the tapered cap

72. From the aforesaid, it will be understood whenever the head 13 is not in engagement with the lug 63 the spring action in the needle bar will force the gripping jaws into the tapered cap 72, and cause such jaws to grasp the needle. The spring action of the lower needle bar acts alternately therewith in the same manner.

A presser foot 75 is provided to engage and retain the work in position during the sewing operation. This foot is secured to a holder 76 clamped to the lower end of a spring tensioned rod 77 which is guided in the lugs 63 and 64 of member 65. The rod 77 is provided with a block 78 fitting in the space between the rear wall of member 65 and a strap 79 secured to a portion of member 65 and in this manner tends to retain the presser foot in alignment with the needle bars. The upper end of the rod 77 is provided with a collar 80 normally abutting a forked block 81 fastened to one end of a pivot shaft 82. One end of shaft 82 is mounted on a projecting lug 83 of member 63 and has its other end mounted in an extending lug 84 of a bracket 85 secured to the wall 27 of head 11. At a point 25 along the length of shaft 82 is mounted an actuator arm 86 carrying a stud supporting a head 87 which holds one end of a rod 88 connecting to a link 89 (Figure 1) pivoted at 90. A manually operated plate 91, adjustably mounted on a rod 92 when moved in the direction indicated by the arrow, turns a stud 93 causing an arm 94, fixed thereto, to descend, and trip the rear end of link 89 whereby its opposite end is caused to rise, and through its connections turns shaft 35 82 and block 81 thus lifting collar 80, rod 77 and consequently the presser foot 75. By lifting the presser foot the operator may readily inspect the work or locate new work in sewing position.

When the upper needle bar 55 ascends, causing the needle to pull the thread through the work, the sudden thrust or piercing tends to overcome the spring pressure of rod 77 and lifts the presser foot 75 from the work. It is desirable to have the spring 95 of rod 77 weak enough to allow the presser foot to yield in order to allow the work to be readily manipulated, prevent undue pressure on the work, and to overcome any excess movement thereof. A spring actuated arm 96 may be provided, which is in close relation with the upper end of rod 77 so that the rod in moving upward will strike the end of the arm 96, and be forced back, thereby tending to maintain the presser foot 75 in its normal position. Arm 96 is mounted on a pivot stud 97 carried by a bar 98 suspended from head 11. A spring 99, having one end anchored to a post 100 in head 11 and its other end attached to arm 96 acts normally to hold an adjusting screw 101 in abutment with a stop 102. The screw 101 is provided so that the gap between rod 77 and arm 96 may be varied to best suit conditions and when properly set the screw is locked in position by any suitable means, such as a knurled nut 103.

65 The driven sprocket 42 (Figures 1 and 2) imparts motion to a chain 105 running over a sprocket 106 mounted on a shaft 107 supported in a hub of bracket 108 secured to frame 10. The opposite end of shaft 107 supports a coupling 109 (Figure 5) terminating in a cam surface 110 which imparts up and down motion to the material feed to be described hereinafter. Member 109 supports a short eccentric stud 111 equipped with a roller 112 engaging an elongated slot 113 provided in the lower end of lever 114

fulcrumed on arm 115 which is mounted on the end of a pivot stud 116 secured to frame 10 by a bolt 117. Lever 114 mounts a stud 118 carrying a follower 119 engaging a slot 120 in the head of a slotted member 121 movably mounted in a counterbored portion 122 of plug 123 turnably supported in an aperture of frame 10.

By loosening the thumb screw 126, arm 124 may be moved, and in so doing shift the position of slot 120 in member 121, thereby changing the angular relation of slot 120 and lever 114. It will be apparent, therefore, that the more slot 120 is turned towards the vertical, the greater will be the feeding motion of plate 135 due to the fact that lever 114, which is pivoted upon lever 115, will be raised a greater amount; lever 115 also will be rocked a proportionately greater amount. If it be desired to decrease the movement of plate 135, the slotted member 121 will be adjusted in the opposite direction so that the slot therein will be moved more towards the horizontal. Since lever 115 is fastened to a fork 127 connected to a material feed arm 128, the resulting to and fro motion imparted to arm 128 can be varied, thereby making it possible to adjust the length and make longer or shorter stitches as required. The up and down movement of arm 128 is imparted by a cam 110 with which coacts a cam follower 129 provided on an arm lever 130 loosely mounted on stud 121a. The arm 131 of lever 130 is connected to one end of an adjustable link 132 in turn connected to a depending arm 133 of member 128.

Material feed plate 135, attached to arm 128, is provided with a corrugated or toothed work feeding surface adapted to engage and advance the work. This plate may be of the usual type employed in sewing machines and is arranged to project upwardly through a slot in plate 13 over which the work is fed to and from the needle. As each stitch is completed, the arm 128 through its connections, is caused to index, that is, the arm descends slightly below the level of throat plate 13 leaving the work resting thereon and then the arm moves up, engages and advances the work in readiness for the next stitch, the work remaining in this position while the plate 135 returns to its original position.

The right end of arm 128 (Figure 3) is mounted on a pivot stud 140 supported in lugs 141 of an arm 142 loosely mounted on stud 134. One end of this stud fits into an aperture in a spacing block 143 (Figure 4) secured to frame 10 by a bolt 144, the opposite end of the stud being provided with a collar 145 tending to retain the arm 142 in position.

Referring to Figures 3 and 4, the looper cam 43 engages a cam follower 146 mounted on a stud 147 carried by an arm 148 secured on a cross shaft 149. The shaft 149, which at one end is supported in a hub 150 of support 65, and its other end in a bracket 85 attached to wall 27, is provided with an arm 151 carrying a tension spring 152 connected to an arm 153 mounted on a stud 154 secured in a lug 155 of member 11, this spring tending to keep the cam follower 146 in engagement with cam 43.

A looper 156 attached near the free end of shaft 149 (Figure 4) at its lower end is provided with a pointed finger 157 and a thread guide roller 158 which together with a tension finger 159 act to properly tension the thread and control its movement with respect to the needle and work. The looper or tensioning member 156 has a return or relieving motion as the needle 75

goes down in the material in order to supply the necessary slack in the thread T. If this slack were not supplied then the eye of the needle would be pulling off the needed amount of thread, which would result in very severe treatments of the thread and needle.

Finger 159 is secured to an arm 160 loosely mounted on shaft 149, and placed adjacent each end of the hub of arm 160 are fiber washers 161-161 which serve to maintain frictional contact with looper arm 156, with the cooperation of a compression spring 162 positioned between and bearing against a fixed collar 163 and a collar 164 loosely mounted on the shaft 149. The finger 159 is normally held inoperative by means of an extension 165 of the upper actuator arm 57, as seen in Figure 3, its movement being controlled by the travel of the upper needle bar 55. As the upper needle bar and the actuator arm ascend, the extension 165 abutting the tapered portion 166 of finger 159 moves upwardly out of engagement therewith and thereby permits the finger to move inwardly adjacent the needle 70. Finger 159 is moved inwardly by a spring actuated plunger 167, situated in the base of support 65, which plunger may be equipped with lock-nuts, resting against an open end slot 169 at the tail end of arm 160 for adjusting the limits of inward movement of plunger 167. The amount of travel of finger 159 inwardly is governed by a stop screw 170, located at the lower end of arm 160, which when it abuts the base of member 65 arrests further movement of the arm and finger. As finger 159 moves inwardly, it engages the thread along one side of the needle and moves it out of the path of the needle in order to prevent the latter from splitting it as the needle moves downwardly into stitching position. Finger 159 also assists in feeding the thread and imparting the correct amount of tension thereto. This is effected by the gentle pulling action of the finger on the thread, which finger kinks the thread adjacent the needle and thereby also prevents undue sliding movement of the thread through the needle in a sewing movement. In this manner the thread making stitches are applied under proper tension to the work. Means described hereinafter are also provided for performing similar functions on the underside of the work.

Referring to Figures 3, 4 and 8, the mechanism for pulling the loop as formed from the thread will now be described. A gear 175 meshing with the gear 44, but rotating at a greater speed, is fixed to a shaft 176 mounted in suitable bearings 177 of head 11 and of a stationary member or drum 178 which is supported by head 11 and a rod 179 extending from frame 10. A gear 180 mounted on the opposite end of shaft 176 meshes with a gear 181 mounted on a shaft 182 supported on frame 10 and a bearing of drum 178. The opposite end of shaft 182 is equipped with a gear 183 in mesh with a ring gear 184 rotating upon a stationary disk 185 secured to drum 178.

In order to pull the loose end of the thread through the work, a thread puller 186 provided with a pointed thread-engaging end is mounted so that it may rotate around the periphery of the stationary drum member 178. The chief function of the thread puller is to engage the loop of thread formed on alternate movements of the needle and pull the thread through the work, and dispose it about the periphery of the drum in such a manner that the danger of snarl-

ing, fouling or breaking the thread is practically eliminated. Reference to Figures 1, 3, 8, 9 and 10 shows that the thread puller 186 is fixed to the outer end of a carrier arm 187, which is pivotally mounted on a stud 188 fixed at the axis of the drum member 178. In order to operate arm 187 and its thread puller 186, a roller 189 is mounted so that it may travel in a longitudinal runway 190 formed in said arm (Figure 3). The roller is mounted upon a pivot stud 191 extending from one side of the ring gear 184. The rotation of ring gear 184, therefore, drives the thread puller 186 in its circular path about the periphery of drum 178 because of the rotation of arm 187 around pivot 188. Runway 190 is formed by a pair of bars 192 attached to and spaced properly by a portion of arm 187. The outer end of arm 187 is also provided with a curved guide plate 193 adapted to engage a tape 194 partly circling the drum 178, which tape acts to maintain the thread in orderly fashion and also prevents whipping of the thread as it is placed around the drum in a manner to be described hereinafter.

The provision of a slidable connection between the ring gear 184 and the arm 187 enables the thread puller to move rapidly at the time it first engages the loop of thread for pulling loose portions thereof out of the work, and then as it continues its angular movement it moves slower and slower until it reaches approximately the nine o'clock position (see Figure 3) or about 270° from the point where it pulls the thread at its fastest rate of speed. From that point on the puller gains speed as it returns to pull the thread back through the work again. In this manner the thread is always rapidly pulled through the work out of the way of the needle and there is no possibility for the needle bar engaging with the puller. A brush S may be fixed beneath the drum 198, as shown in Figures 3, 10 and 13, in order to act as a brake and apply a frictional force upon the thread as it is being pulled from the drum. This adds additional control in handling the thread and prevents it from whipping about or tangling in any manner.

Tape 194 (Figures 1, 3, 8 and 10) is led around a roller 195, supported by an upright 196 extending from a flange 197 of a second stationary drum 198 and its end is clamped between plates 199 of a yieldable stud 200 supported in member 12. The other end of tape 194 is led around a roller 201, supported by an upright 202 extending from flange 197, and its end is clamped by plates 203 supporting a tension spring 204 connected to an arm 205 secured to flange 197, the spring serving to apply the proper tension to tape 194.

Referring to Figure 4, the gear 181 in turning shaft 182 imparts motion to a gear 210 in mesh with a gear 211 integral with a cam 212 loosely mounted on shaft 176. The ratio of gears 180 and 181 is such that shaft 176 makes two revolutions for each revolution of shaft 182, whereby the cam 213 on shaft 182 and the cam 212 and a cam 214 integral with cam 212 will rotate at one-half the speed of members fixed on shaft 176. The cam 213 (Figures 4 and 7) engages a cam follower 215 on an eccentric stud 216 of a cam lever 217 mounted on a pivot stud 218 secured in head 11. The tail end of lever 217 supports a spring 219 connected to a post 220 carried by a frame 10, which spring acts normally to hold the follower 215 in engagement with cam 213. The upper end of lever 217 (see Figures 6 and 7) is provided with an open end slot 221

adapted to engage a pin 222 of a block 223 sliding in a runway 224 of a bracket 225 secured to head 11. The block 223 is provided with cam tracks 226 and 227 engaging cam follower 228 carried by arms 229 and 230 mounted on pivot studs 231 and 232, respectively, extending from the base of bracket 225.

The movement of block 223 in one direction causes the cam tracks 226, 227 through cam followers 228 to swing their respective arms 229 and 230 closing around the needle 70 and grip the thread. The arms retain this position and hold the loop of thread straight while the thread puller 186 engages the loose end of the thread and advances a considerable distance around the periphery of the drum. The block 223 in moving in the opposite direction reopens the arms and permits the lower needle bar to pass upward. When the arms 229 and 230 are in their gripping position, the eccentric stud 216 of cam lever 217, is adjusted so as to be clear of the cam track, thus assuring a tight grip of the thread. It will be seen that arms 229 and 230 when gripping the thread hold that portion which may be called the fixed end of the thread with respect to the work (see Figures 8 and 10). In this manner the amount of tension on the stitch just made is minimized or so limited that the thread cannot be broken by the action of the puller, nor can it be tensioned in the work or pulled out of the work by the action of the puller.

The bracket 225 is provided with an extending lug 233 (Figures 4, 6 and 7) supporting a loosely mounted stud 234 which at its lower end has fixed thereto a bell crank lever 235, said lever being actuated by a cam 236 (Figure 4) fixed on shaft 176. Cam 236 actuates a cam follower 237 of a cam lever 238 mounted on a pivot 239 carried by a bracket 240 attached to frame 10. The upper end of lever 238 supports one end of a link 241 connected to bell crank lever 235 whereby motion is imparted to a hooked tension finger 242 clamped in or integral with a block 243 which is secured to the stud 234. Once during each cycle of cam 236, the follower 237 is forced inward by a spring 244 to engage the depressed portion 245 of the cam whereby the finger 242 is caused to move in the direction of the arrow (Figure 6) and tension the thread. Finger 242 also guides the thread out of the path of the traveling needle. A spring 246 is connected at one end to the lever 235 and at its other end is attached to an adjustable screw 247 (Figure 3) turnably mounted in frame 12, thereby providing means for tensioning the finger 242. Finger 242, therefore, is actually responsible for tensioning and throwing the thread out of fouling position with respect to the needle on the up stroke thereof, and for throwing the thread out of fouling position on the down stroke of the needle.

The bracket 225 supports a thread guide 248 and a pivot stud 249. The stud 249 supports a swingable thread clamp member 250 which terminates in an arm 251. A cover 252 has the same general contour as member 250, with the exception of the arm portion which is secured to the former by screws 253. Member 250 is provided with a track 254 in which is mounted a slideable thread gripper 255 having at an upper end, a hook portion 256 adapted to engage the thread and advance it toward the rounded extending portion 257 of member 250 which coacts therewith to clamp the thread. Member 255 is moved in and out by means of a cam actuated lever 258 which engages the rounded tail portion 259 of

member 255. Lever 258 is pivoted on a stud 260, supported in member 225 and its lower end is equipped with a cam follower 261 engaging in a cam track 262 of cam 214. The engagement of lever 258 with the rounded portion 259 is maintained by a tension spring 263 spanned between a post 264 in the cover 252 and a post 265 in the sliding member 255.

The up and down movement of members 250, 252 and 255 is effected by means of a cam actuated link 266 mounted on a stud 267, in arm 251 and connected to a cam lever 268 pivoted on a stud 269 supported by head 11. Lever 268 derives motion from cam 212 having a cam track 270 engaging a cam follower 271.

The operation involved in stitching the work will now be described briefly; with the needle 70 grasped by the lower needle bar 56 (Figure 8) the needle bar descends its full stroke, then ascends slightly and dwells, the slight upward motion forming a loop L in the thread T. At this time the arms 229 and 230 close around the needle 70, grip the thread, and prevent unnecessary pulling of the stitch as the thread puller 186 enters loop L and starts to pull the free end F of the thread through the work. The free end F of the thread is guided into a thread trap 272 of member 248 as it comes out of the opening 273 formed by the stationary drums 178 and 198 as shown in Figure 11. As the thread puller 186 moves continuously it pulls the free end of the thread from the work and this loose portion B is laid by the puller upon the periphery of the drum 198 as the puller moves in a clockwise direction as seen in Figure 9. It will be observed that puller 186 moves beneath tape 194 for the greater part of its travel and hence the thread cannot be thrown away from the drum or become tangled in any manner. With the puller 186 in this latter position the thread is wound partly around a groove 274 in the puller formed at an angle therewith as seen in Figure 12, whereby one thread A is caused to be guided onto a shelf 275 of drum 178 and the other loop of the thread B is led into a groove 276 provided in the periphery of drum 198 and the free end F is in the opening 273. As the thread puller 186 (Figure 9) engages the loop of thread and travels about its course, it disposes the loose portion of the thread (that part designated B, Figure 9) in groove 276 of the drum, and at the same time the fixed portion A, which is held by grippers 229, 230 is guided by means of stationary guide 271 mounted upon brackets 225 between the open jaws of auxiliary grippers 255, 257 and onto the shelf portion 275 of the drum (Figures 11, 12 and 13). When the thread has been so positioned with respect to gripper jaws 255, 257 and as the jaws 229 and 230 open, the thread is gripped by the auxiliary gripper and the lower needle bar 56 ascends, whereupon the needle 70 is projected through the work, which has in the meantime been advanced one stitch length by material feed 135 and the needle is then grasped by the upper needle bar 55. It will be seen, therefore, that during the pulling of the thread the fixed portion thereof is always clamped either by the grippers 229, 230 or by auxiliary grippers 255, 257 and excess tensioning of the thread is prevented. The gripper mechanism 250-252 rises in unison with the lower needle bar and holds the thread somewhat taut. In ascending, the gripper carries the thread over the guide 271 and positions it in trap 272 between jaws 272a and 272b, as seen in Figure 15. At the time the thread is advanced by the hook

256 towards portion 257 the thread A (Figure 12) is moved from the shelf 275 and positioned as shown in Figure 13, in a cut back portion of the shelf which holds the thread on the drum against removal. The gripper in swinging upward moves thread A to a position F (Figure 13) and when the gripper opens the thread will become lodged in trap 272. In this manner the thread is disposed beyond the range of operation of thread puller 186. Hence the danger of pulling more than one loop of thread around the drum 198, and possible fouling of the machine, is practically eliminated. Shortly before transferring the needle to the upper needle bar, the tension finger 242 moves in the direction of the arrow (Figure 6) and tensions the thread, and then retreats. In tensioning the thread, the finger also functions to prevent fouling of the thread by moving it out of the path of the needle 70 as it ascends.

20 The upper needle bar 55 having grasped the needle 70 ascends its full stroke and then descends slightly forming a loop in the thread. The front of the loop is then engaged by the looper finger 157, which sweeps across from a position to the right of the needle 70 (Figures 8, 9 and 10) and pulls the thread over its roller 158 to a position shown in Figure 10. The travel of the looper finger is such that it will pull sufficient thread and thereby prevent the formation of over-tight stitches. Roller 158 allows the thread to slide over it with a minimum amount of friction when the looper finger 157 is pulling the thread through the work. Finger 159, which is mounted at the opposite side of the needle bar 55 with respect to looper arm 156, advances substantially simultaneously with the arm 156 from the position shown in Figure 8, engages the rear portion of the looped thread and carries it to the position shown in Figure 10. As a result 30 of its movement, finger 159 removes much of the danger of the thread being cut or otherwise fouled by the needle, and due to the fact that it makes a kink in the thread adjacent the needle the thread will have less tendency to slide through the eye of the needle, as the needle is moved downwardly through the work. This will effect the formation of more uniform stitches. In a like manner the disposition of the 35 thread to one side by the finger 159 prevents fraying of the thread in passing through the eye 71 of the needle.

The material feed 135 now advances the work the length of one stitch, and the tension finger 242 acts to displace the thread from the path 40 of the descending needle 70 and thereby prevents the thread from being fouled as the needle forms its stitch, and before it is again grasped by the lower needle bar 56. Shortly before the upper needle bar 55 descends, the gripper mechanism 250-252 retreats to its down position and in doing so leaves the free end F of the thread held in the slot 272 of member 248 out of the path of the thread puller 187.

Referring to the modification shown in Figure 55 16, the general operation of the feed arm 128 is the same as hereinabove described. Mechanism has been provided, however, which makes it possible to adjust it for controlling the length of the normal stitching and make long or shorter 60 stitches as the case may be according to the requirements with respect to the particular work being sewed. As an example, in sewing the sides of the fingers of gloves the normal stitch length is generally used for the major portion of each glove. However, when the operative proposes to

sew the tip portion of the fingers, the normal stitch may be found to be too long for satisfactory work, and hence I have provided means to shorten the stitch. At this time, the operator depresses a foot pedal which through connections to be described presently, changes the position of the stitch control member 121 to produce shorter stitches for sewing the finger tip portion of the glove. When the sewing of the tip portion is completed, the operator's foot is released from the pedal and normal stitching will be resumed.

An arm 306 (Figure 16) is clamped to member 121 and at its lower end supports a forked head 301 and a head 302 connected by means of a rod 303 to an arm 304 fixed on a pivot shaft 305. An arm 306, also fixed on shaft 305, is actuated by a link 307 connected to a foot pedal 308 mounted on a pivot 309. The forked head 301 carries an adjustable link 310 which at its other end is provided with knurled nuts 311 and 312 which are turnably and slidably mounted in an aperture 313 of a holder 314 secured in a suitable manner to the frame of the machine. The aperture 313 is open at the top and exposes a portion of the shanks 315 of the nuts 311 and 312, the exposed portion of the shanks being engaged by prongs of a flat spring 316 which tend to hold said nuts from turning after the final adjustments have been made.

The knurled nut 311 provides means for adjusting the position of member 121 to obtain the length of stitch best suited for different types of work. A spring 317 having one end attached to arm 306 and its other end secured to a stationary part of the machine (not shown) normally tends to hold the shoulder 318 of nut 311 in engagement with holder 314. The knurled nut 312 governs the length of the short stitch. That is, with the foot pedal 308 depressed the rod 303 will move arm 306 and consequently change the position of member 121 by varying the throw of lever arm 114 which controls the horizontal distance traveled by bar 128. The movement of arm 306 causes link 310 to remove the shoulder 318 of nut 311 from holder 314 and advance nut 312 until its shoulder 319 abuts the other end of holder 314 thus halting further movement of arm 306. Member 121 retains this position until the foot pedal 308 is released, whereupon spring 317 restores the device to its former position. It will be apparent that the greater the distance between shoulder 319 and the end of the holder 314, the greater will be the movement of arm 306 to set member 121, which consequently results in shorter stitches.

Referring to Figures 17 and 18, another modified stitch control device is shown in which alternate short and long stitches are automatically produced for decorative work. According to this embodiment, a driven sprocket 320 fixed on a shaft 321 imparts motion to the eccentric 111 and cam 110 to actuate the material feed arm 123 in the same manner as shown in Figures 3 and 5. A gear 322, fixed on shaft 321, meshes with and drives a gear 323 and its attached gear 324 loosely mounted on stud 121a, while the gear 324 in turn drives a gear 325 and a cam 326 loosely mounted on shaft 321. In this manner, the gearing 322, 323, 324 and 325 drives the cam 326 at one-half the speed of cam 110. Cam 326 engages a cam roller 327 carried by a cam lever 328 mounted on shaft 121. Lever 328 is adjustably attached to an arm 329, clamped on shaft 121 by a thumb screw 330. The lower

portion of arm 329 is provided with an elongated slot 331 adapted to engage thumb screw 330. By loosening the thumb screw 330, the arm 329 may be moved and in so doing shift the position of slot 120 of shaft 121 resulting in more or less movement of arm 128 as heretofore mentioned.

The cam 326 has a high portion 332 and a lower portion 333, the surface 332 being considerably longer than 333 and therefore when it engages follower 327 it holds the slotted head of stitch control member 120 in a position to produce a long stitch, as the follower 327 rides off surface 332 and approaches surface 33, the slotted head of member 120 is turned to a position to produce a short stitch. The continuous rocking of the slotted head results in alternate long and short stitching of the work.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a sewing machine of the class described, the combination with a pair of alternately operating needle bars, of a needle, means for alternately connecting the needle with each bar and projecting a thread having a fixed and a loose end through the material to be sewed, thread gripping means, means mounting said gripping means adjacent one of said bars, and means operating when said needle is held by said last-named bar for gripping the thread against movement relative to said needle at the conclusion of each stitching operation.
2. In a sewing machine, a needle, needle bars for moving said needle with a thread having a fixed and a free end in opposite directions through work to be sewed, mechanism adjacent to and operating in conjunction with one of said bars for gripping the thread adjacent said needle, auxiliary gripping means coacting with said mechanism, and means for releasing the thread in said mechanism while said auxiliary means hold said thread gripped.

3. In a sewing machine, needle bars for moving a needle with a thread having a fixed and a free end in opposite directions through work to be sewed, mechanism operating in conjunction with one of said bars for tensioning said thread at the conclusion of a sewing operation, a device coacting with said mechanism for gripping said thread, means for releasing the thread in said mechanism, means for simultaneously moving said device and said last-named bar as said needle advances towards said work, a thread trap, and means for releasing the thread from said device and transferring it to said trap.

4. In a short thread sewing machine, needle bars for moving a needle with a thread having a fixed and a free end in opposite directions through work to be sewed, mechanism operating in conjunction therewith for gripping the thread at the conclusion of a sewing operation, a thread trap, means for moving said mechanism and one of said bars simultaneously towards the work, and means for freeing said thread from said mechanism and transferring it to said trap.

5. In a sewing machine of the under and over type, a needle, opposed reciprocating needle bars, means for alternately connecting said needle with said bars for projecting said needle with a thread

having a fixed and a free end through work to be sewed, thread grippers, means for moving said grippers cyclically into gripping engagement with a portion of said thread for holding the fixed end of said thread against tension, and means for pulling the loose end of the thread through the work while the fixed end is so held.

6. In a sewing machine, the combination with a needle, and means for moving said needle having a thread with a fixed and a free end back and forth through work to be sewed, of means engaging and gripping a portion of said thread to hold said fixed end against excess tension, auxiliary gripping means coacting with said first-named gripping means to grip another portion of said thread, and a puller for pulling the free end of the thread through the work while the thread is so gripped.

7. In a sewing machine, the combination with alternately operating needle bars, of a needle, means for connecting said needle with said bars for projection with a thread having a fixed and a free end through work to be sewed, clamp means positioned adjacent one of said bars and acting in conjunction therewith for clamping a portion of said thread including the fixed end of said thread, a thread puller for pulling the free end of said thread through the work, auxiliary means coacting with said clamp means for holding a portion of said thread, and means positioned to receive the free end of said thread as it is pulled through said work.

8. In a sewing machine, the combination with a needle and opposed needle bars, of means for alternately connecting said needle with said bars and projecting said needle with a thread having a fixed and a loose end through work to be sewed, a drum located adjacent one of said bars, a puller device cooperating therewith to pull the free end of the thread through the work and lay it on said drum, thread gripping means adjacent one of said bars, and means operating one of said gripping means cyclically to grip and hold said fixed end of said thread to limit the amount of tension on said thread during the operation of said puller.

9. The method of forming a series of under and over type stitches, comprising moving a double pointed needle, with an eye located between said points and threaded with a thread having a fixed and a loose end, back and forth through the work to be stitched, including gripping the thread adjacent the needle after its movement through the work, pulling the free end through the work while it is so gripped, releasing the gripped thread, moving said thread out of the path of travel of said needle, projecting said needle through said work, drawing said thread part way through the work, tensioning said thread, pulling a sufficient quantity of thread through the work to provide sufficient thread for the stitch thus made, and releasing said tension, and again projecting said needle through the work.

10. In a sewing machine, the combination with a needle, a pair of opposed reciprocating needle bars, and means for alternately transferring the needle with a thread having a fixed and a loose end from one needle bar to another through work to be sewed, of a puller for pulling the free end of the thread through the work, means for moving said puller, means for holding the fixed end of the thread against excess tension while the puller is pulling the thread through the work, a thread receiving member having a thread receiving surface positioned to receive the loose

end of said thread as it is pulled through the work by said puller, and means positioned adjacent said member for holding the loose end of the thread on said surface.

5 11. In a sewing machine, the combination with a needle, a pair of opposed reciprocating needle bars, means for alternately transferring the needle with a thread having a fixed and a loose end from one needle bar to another through work to be sewed, of a puller for pulling the free end of the thread through the work, means for holding the fixed end of the thread against excess tension while the puller is pulling the thread through the work, a drum positioned to receive the loose end of said thread, a belt encircling a substantial portion of the periphery of said drum and holding the loose end of the thread on the periphery thereof, and a device for controlling the movement of said thread on said drum.

12. In a sewing machine, the combination with a needle, a pair of opposed reciprocating needle bars, means for alternately transferring the needle with a thread having a fixed and a loose end from one needle bar to another through work to be sewed, of a puller for pulling the free end of the thread through the work, means for holding the fixed end of the thread against excess tension while the puller is pulling the thread through the work, a drum positioned to receive the loose end of said thread, a belt encircling a substantial portion of the periphery of said drum and holding the loose end of the thread on the periphery thereof, and a device for controlling the movement of said thread on said drum.

13. In a short thread sewing machine, a pair of alternately operating needle bars, a needle, means for alternately connecting said needle with said bars to project a thread back and forth through work to be stitched, means operating in conjunction with one of said bars for tensioning the thread, a drum, a thread puller operating while said thread is tensioned for pulling it through the work and winding it on said drum, and a thread brake coacting with said drum to control the movement of the thread from said drum.

14. In a sewing machine of the class described, the combination with a needle, of a pair of opposed needle bars, a work support and means for feeding work along said support, of means for alternately operating said needle bars to grip said needle having a thread with a fixed and a free end for projecting it through the work to be sewed, means for clamping said thread at the conclusion of a stroke of said needle, a drum mounted on one side of said support, a thread puller mounted for movement concentric with said drum, means for moving said puller to seize said thread and lay it about said drum, and a belt arranged about a substantial portion of the periphery of said drum beneath which said puller travels for holding the loose portion of the thread upon said drum.

15. In a sewing machine, the combination with a needle, and a pair of opposed alternately operating needle bars, of means for alternately connecting the needle with each bar for projection through work to be stitched, said needle having a thread with a fixed and a free end, means for clamping the thread at the conclusion of a movement of said bars, a thread receiving mem-

ber, a thread puller for pulling the free end of the thread through the work while the other end of said thread is clamped and disposing said thread upon said member, means for supporting the work to be stitched between said needle bars, and means mounted beneath said supporting means and projecting therethrough operating in timed relation with the movement of said bars and puller for feeding the work along said supporting means to said needle.

16. In a sewing machine, the combination with a work support and means for feeding the work over said support, of opposed needle bars mounted on opposite sides of said support, a needle, and means for alternately connecting said needle to said bars for projection with a thread having a fixed and a loose end through said work, means for minimizing the tension on the fixed end of the thread at the conclusion of the movement of said bars, a thread puller for pulling the loose end of the thread through the work, a drum, guide means on said drum for disposing the thread in proper position thereon, and means movable into and out of engagement with said thread for tensioning said thread as it is being pulled from said drum during the next stitching operation.

17. In a sewing machine, the combination with a work support, and means for feeding the work over said support, of opposed needle bars mounted on opposite sides of said support, a needle, and means for alternately connecting said needle to said bars for projection with a thread having a fixed and a free end through the work, means movable into and out of engagement with said thread for minimizing the tension on the fixed end of the thread at the conclusion of each movement of said bars, a thread puller for pulling the loose end of the thread through the work, a device for receiving and guiding said thread as it is pulled through said work by said puller and means coacting with said device for controlling the movement of said thread from said device.

18. In a sewing machine, the combination with a work support and opposed alternately operating needle bars located on opposite sides of said support, of a needle, means for alternately connecting said needle with said bars for projecting it with a thread having a fixed and a loose end through work to be sewed, and thread displacing devices on opposite sides of said support and located adjacent each of said bars, and mechanism for operating each of said devices alternately prior to the movement of the bar holding the needle for moving the thread out of the path of movement of said needle.

19. In a sewing machine, the combination with a needle and means for projecting said needle and a thread back and forth through work to be stitched, of grippers for clamping and tensioning said thread against movement relative to said needle, and means located adjacent said grippers for moving said thread laterally out of the path of movement of said needle.

20. In a sewing machine, the combination with a needle and means for projecting said needle and a thread through work to be sewed, of thread tensioning means, and means acting in conjunction therewith for moving said thread laterally out of the path of movement of said needle, said last-named means comprising a yieldingly mounted finger, and means for moving said finger across the path of movement of said needle.

21. In a sewing machine of the class described,

a needle, means for moving said needle with a thread having a fixed and a free end in opposite directions through work to be sewed, mechanism operating in conjunction with said means for gripping said thread adjacent said needle, means for pulling the free end of said thread through said work while it is so gripped, auxiliary means cooperating with said mechanism to grip said thread, means for causing said mechanism to release said thread, and means for moving the thread out of the path of the needle prior to its movement in an opposite direction.

22. In a sewing machine of the class described, a needle, means for moving said needle with a thread having a fixed and a free end in opposite directions through work to be sewed, mechanism operating in conjunction with said means for gripping said thread between said work and said needle, means for pulling the free end of said thread through said work while said thread is so gripped, auxiliary means cooperating with said mechanism to grip said thread, means for causing said mechanism to release said thread, means for moving the thread out of the path of the needle prior to its movement through the work in an opposite direction, and means for moving said auxiliary means in conjunction with the travel of said needle to displace a portion of said thread laterally with respect to the line of movement of said needle.

23. In a sewing machine, the combination with a pair of opposed alternately operating needle bars, of a needle, a work support, and means for feeding work along said support, of means for connecting said needle alternately with each bar for projection with a thread having a fixed and a loose end through said work, a drum located adjacent said support, a thread puller for pulling the free end of the thread through the work and disposing it about the periphery of said drum, means for applying tension to said fixed end of said thread during the operation of said puller, and means mounted on opposite sides of said support for alternately moving the thread out of the path of movement of the needle.

24. In a sewing machine, the combination with a pair of opposed alternately operating needle bars, a needle, a work support, and means for feeding work along said support, of means for alternately connecting said needle with each bar for projection with a thread having a fixed and a loose end through said work, a drum located adjacent said support, a thread puller movable about the periphery of said drum for pulling the free end of said thread through the work and disposing it about said drum, means for applying limited tension to said thread during the operation of said puller, and devices mounted on both sides of said support for moving the thread out of the path of movement of said needle, said devices comprising intermittently operated fingers, and means for moving said fingers in timed relation with the movements of said needle.

25. In a sewing machine of the class described, the combination with a needle, a pair of opposed needle bars, a work support, and means for feeding work along said support, of means for alternately operating said needle bars to grip said needle having a thread with a fixed and a loose end and project it back and forth through the work, means located at one side of said support for tensioning said thread, a thread support positioned adjacent said tensioning means, a thread puller for pulling the free end of said thread through said work while it is so tensioned, and

laying it upon said thread support, and a member movable between said tensioning means and work support for displacing said thread out of the path of movement of said needle at the start of each alternate stroke of said needle.

26. In a sewing machine of the class described, the combination with a needle and a pair of opposed needle bars, of means for alternately operating said needle bars to grip said needle with a thread having a fixed and a free end for projecting said needle back and forth through the work to be sewed, of means for clamping the thread at the conclusion of alternate movements of said needle, a thread puller operating in conjunction with said clamping means for pulling the free end of the thread through the work while it is clamped, a drum positioned to receive said thread as it is pulled through the work by said puller, and means positioned about said drum for holding said loose thread thereon as said puller disposes it thereabout, said means comprising a yieldably mounted belt arranged circumferentially about the major portion of said drum.

27. In a sewing machine, the combination with a pair of alternately operating needle bars, of a needle, a work support, means to alternately connect the needle with each bar for projecting it with a thread having a fixed and a free end through said support, means to move the thread out of the path of said needle prior to the stitching operations thereof, a drum located adjacent said support, a flexible element arranged peripherally about a substantial portion of said drum, and means moving between said element and the periphery of said drum for pulling the free end of the thread through the work and depositing it about said drum beneath said element.

28. In a sewing machine of the class described, the combination with a work support, and means for feeding work to be sewed along said support, of a needle, a pair of alternately operating needle bars for projecting said needle and a thread having a loose and a fixed end back and forth through said work, thread gripping means located on one side of said support for gripping said thread on one movement of said needle through said work, looping mechanism on the other side of said support for pulling a part of the thread through the work, and means acting in conjunction with said mechanism for tensioning said thread.

29. In a sewing machine of the class described, the combination with a needle and a pair of opposed alternately moving needle bars, of means for alternately connecting the needle with each bar for projection through the work to be stitched, said needle being provided with an eye between its ends and a thread having a fixed and a free end, means for clamping the thread at the conclusion of one stroke of said needle and one of said bars, a thread puller for pulling the free end of said thread through the work while it is so clamped, means for releasing the thread at the conclusion of the pulling operation, means for moving the thread out of the path of said needle prior to its movement in the opposite direction, means for moving said needle through the work in the opposite direction, a looper for pulling said thread on one side of said needle after said movement, a finger arranged to engage said thread on the other side of said needle, and means for advancing the work during the alternate movements of said needle bars.

30. A sewing machine of the class described

comprising, a pair of spaced reciprocating needle bars, a needle, means to connect the needle alternately with each bar for projection through the work, a thread looper movably mounted adjacent one of said needle bars and arranged to engage the thread on one side of the needle in said bar, a tensioning finger cooperating with said looper to engage said thread on the opposite side of said needle, and means for moving said looper into engagement with said thread in advance of the movement of said finger into engagement with another portion of said thread on said opposite side of said needle.

31. In a sewing machine, a plurality of thread gripping members, and mechanism for operating each of said members in succession to grip and tension a thread and prevent movement thereof relative to a needle, a thread puller for pulling a loose end of said thread through work being sewed while said thread is gripped by one of said members, said mechanism including means for opening one of said members to release said thread when said thread puller has pulled the loose end of said thread through said work, and means for operating the other of said gripping members to displace the thread laterally out of the path of said needle, and a drum about which said loose thread is placed by said thread puller.

32. A sewing machine of the class described, comprising a pair of spaced reciprocating needle bars, a needle, means to connect the needle alternately with each bar for projection back and forth through the work, a thread looper movably mounted adjacent one of said needle bars, a thread guide roller mounted on said looper for engaging said thread, and a thread tensioning finger movably mounted on the opposite side of said last-named bar cooperating with said looper.

33. In a short thread sewing machine having a needle, and means for projecting said needle and a thread having a fixed portion and a loose end through work to be stitched, a thread receiving device comprising a plurality of spaced surfaces, a thread puller for pulling said thread, and means for laying the loose end of said thread on one surface while part of the fixed portion is being disposed upon another surface.

34. In a sewing machine, the combination with means including needle bars for projecting a needle with a thread having a fixed and a free end through work to be sewed, of means for tensioning the thread on both sides of the work, a puller associated with said needle projecting means for pulling the loose end of the thread through the work, and means for moving said puller in timed relation to the movement of said bars.

35. In a short thread sewing machine having a needle and means for projecting said needle and a thread having a fixed and a free end through work to be stitched, the combination with a thread receiving device provided with a plurality of spaced surfaces, of a thread puller, means for moving said thread puller to lay one portion of said thread temporarily on one of said surfaces, and a member for guiding another portion of said thread onto another of said surfaces.

36. In a short thread sewing machine having a needle and means for projecting said needle and a thread having a fixed and a free end through work to be stitched, the combination with a thread receiving device provided with a plurality of spaced surfaces, of a thread puller, means for moving said thread puller to lay one portion of said thread temporarily on one of said surfaces,

a member for guiding another portion of said thread onto another of said surfaces, and means for subsequently moving said thread laterally to position it out of the range of action of said thread puller.

37. In a sewing machine, the combination with opposed needle bars for projecting a threaded needle back and forth through work to be sewed, a device located adjacent one of said bars for gripping the thread and holding it against movement relative to said needle, and another means acting in conjunction therewith for gripping said thread along another portion of its length, means for opening said device to release said thread, means for moving said gripping means to displace said thread laterally with respect to the path of movement of said needle, and means for moving said needle bars in timed relation with the movement of said gripping means to project the needle and thread through the work.

38. In a sewing machine, a drum member constructed and arranged to receive a thread laid about its periphery, said drum being provided with a split rim, one portion of which is furnished with a groove and a member associated with said drum and forming therewith a second guide groove whereby it guides the thread on its movement along the drum.

39. In a sewing machine for successively passing a double pointed needle with a thread receiving eye through the work from one side thereof to the other, the combination with opposed needle bars reciprocable toward and away from each other each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, and a gripper arranged to grip a portion of the thread between the last stitch and said puller during the operation of the latter in order to prevent any tension on the stitch as a result of the operation of the puller.

40. In a sewing machine for successively passing a double pointed needle with a thread receiving eye through the work from one side thereof to the other, the combination with opposed needle bars reciprocable toward and away from each other, each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, a gripper arranged to grip a portion of the thread between the last stitch and said puller during the operation of the latter in order to prevent any tension on the stitch as a result of the operation of the puller, a tensioning device having a thread engaging portion, and means causing said portion to pull on the length of the thread between the last stitch and said gripper with a predetermined tension.
41. In a sewing machine for successively passing a double pointed needle with a thread receiving eye through the work from one side thereof to the other, the combination with opposed needle bars reciprocable toward and away from each other, each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, a gripper arranged to grip a portion of the thread between the last stitch and said puller during the operation of the latter in order to prevent any tension on the stitch as a result of the operation of the puller, a tensioning device having a thread engaging portion, means causing said portion to pull on the length of the thread between the last stitch and said gripper with a predetermined tension.
42. In a sewing machine for successively passing a double pointed needle with a thread receiving eye through the work from one side thereof to the other, the combination with opposed needle bars reciprocable toward and away from each other, each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, a gripper arranged to grip a portion of the thread between the last stitch and said puller during the operation of the latter in order to prevent any tension on the stitch as a result of the operation of the puller, a tensioning device having a thread engaging portion, means causing said portion to pull on the length of the thread between the last stitch and said gripper with a predetermined tension.
43. In a sewing machine for successively passing a double pointed needle with a thread receiving eye through the work from one side thereof to the other, the combination with opposed needle bars reciprocable toward and away from each other, each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, a gripper arranged to grip a portion of the thread between the last stitch and said puller during the operation of the latter in order to prevent any tension on the stitch as a result of the operation of the puller, a tensioning device having a thread engaging portion, means causing said portion to pull on the length of the thread between the last stitch and said gripper with a predetermined tension.
44. In a sewing machine for successively passing a double pointed needle with a thread receiving eye through the work from one side thereof to the other, the combination with opposed needle bars reciprocable toward and away from each other, each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, a gripper arranged to grip a portion of the thread between the last stitch and said puller during the operation of the latter in order to prevent any tension on the stitch as a result of the operation of the puller, a tensioning device having a thread engaging portion, means causing said portion to pull on the length of the thread between the last stitch and said gripper with a predetermined tension.
45. In a sewing machine for successively passing a double pointed needle with a thread receiving eye through the work from one side thereof to the other, the combination with opposed needle bars reciprocable toward and away from each other, each having needle jaws adapted to grip a point of said needle, actuating means for said bars and jaws for successively passing the needle and a portion of the thread passing through the needle eye through the work from one side to the other, a thread puller for entering the loop formed by the needle in pulling the thread through the work and pulling one end of the thread free of the work, a gripper arranged to grip a portion of the thread between the last stitch and said puller during the operation of the latter in order to prevent any tension on the stitch as a result of the operation of the puller, a tensioning device having a thread engaging portion, means causing said portion to pull on the length of the thread between the last stitch and said gripper with a predetermined tension, means coating with said device for varying said tension.

CARL W. JOHNSON.
